CULINARY DEVICE

Johanna W. Stein, Cleveland, Ohio

Application November 12, 1935, Serial No. 49,339

3 Claims. (Cl. 107—46)

This invention relates to covering tops or parts of tops of tables or similar devices for culinary purposes such as mixing or kneading or rolling of dough.

5 The objects of this invention are: to provide a means, including a canvas-like pad, whereby a table top, or a part thereof can be covered for culinary purposes; which means is sanitary and can be cleaned easily and prevents impurities of 10 or on a table top from being mixed with material on the pad; the parts of which means can easily be assembled relative to a table top and can easily be disassembled and closely packed and rolled into a bundle for storing thereof; whereby the pad is 15 held against shifting on the table top and the holding effect of the pad is increased when a pad moving pressure is brought onto the pad. Other objects will be pointed out during the description of the device illustrated in the accompanying drawing which forms part of this specification and other objects will become obvious or apparent 20 or will suggest themselves upon an inspection of the drawing and this specification.

In the accompanying drawing, selected for 25 illustrating the present invention:

Fig. 1 is a plan view of a device embodying the present invention and shows a pad on a table top, but not covering the same completely; the holding means for one edge of the pad to one edge of the 30 table; and the other edge being free of either a binder or a securing means.

Fig. 2 is a plan view of a device similar to Fig. 1, also embodying the present invention and shows the pad gripping and table edge engaging members on the front of the table as being of two parts 35 and also shows a binder across the rear end of the pad, a bracket on the rear end of the table, and a resilient member between the binder and the bracket.

40 Fig. 3 is a transverse section taken on line 3—3 of either Fig. 1 or Fig. 2 to show structure and formation of the elements more clearly.

Fig. 4 is a transverse section taken on line 4—4 of Fig. 2 to more clearly show the formation and 45 the relation of parts at the rear end of the table.

Fig. 5 is a transverse section taken on the line 5—5 of Fig. 2 to more clearly show the relations of all of the parts of the present device.

Similar reference characters refer to similar 50 parts throughout the views.

The device shown, being one of the possible embodiments of the present invention, will now be described as to structure and function and operation thereof.

55 The table top 10 is shown as made of wood although it may be made of other material since there is no necessity for any clamping or holding means to be inserted thereinto for the present invention.

60 The pad 11 lies on top of the table top when in

use and is made of flexible material, preferably easily flexible material. The fabric generally known as canvas is quite satisfactory for such purpose although any other cloth-like material can be used. The mesh of the material, however, should not be too coarse so that flour and the like will not easily fall therethrough and dough will not be pressed thereinto. Metal cloth, when used, should be of very fine mesh for above reasons. 10

Referring now specifically to Fig. 1: The element 12 is formed to engage the edge 13 of the table top and also to engage the front edge 14 of the pad 11. The element 12 is made of material somewhat harder and less flexible than the material of the pad 11; bakelite or other materials of a similar nature may be used for this element. In most cases, however, a metal is preferable for this element since it is quite strong and easily bent and formed as required and has sufficient 15 resiliency therein for pad gripping and releasing. Caution must, however, be used in the selection of this material to prevent pollution of material worked upon. 20

Iron and steel present sufficient resiliency required in the pad engaging elements but are subject to rust since salt and similarities usually are present in the material worked upon and may effect deterioration of the material of the elements. 25

Brass and similarities present sufficient resiliency required in the pad engaging elements but, due to the copper content therein, are subject to deterioration and verdigris due to fatstuffs in the material acted upon. 30

Stainless steel present sufficient resiliency required in the pad holding elements and is free of deterioration by rust and is preferred on that account although it is more expensive than iron, 35 steel and brass. 40

Galvanizing, plating, japanning, and similarities may be resorted to for the pad holding elements but, since such procedures only cover and inclose the material or form a coating for the outside thereof, salt, fatstuffs, and such may get in between this coating and the material coated and start deterioration and corrosion even without being noticed at the time. 45

The element 12 (Fig. 3) is formed of one sheet of material and has the flange 15 to engage with the underside of the edge 13, the part 16 to abut the outside of the edge 13, the part 17 to engage with the top side of the edge 13 and the part 18 superimposing the part 17 with the space 19 between the same. The part 18 has the teeth 20 formed thereon similar to teeth in a wood saw. The part 17 has parts thereof partly severed therefrom and bent upwardly to also form the teeth 21, preferably staggered relative to the teeth 20 so that the set of teeth on one part 50 55 60

can press the pad material down into the spaces between the teeth of the opposite part. This structure prevents the teeth from digging into and tearing the pad material.

5 In this illustration, the rear end 22 of the pad 11 is unsupported although a holding means may be provided there. Such structures as the well known vacuum cups serve well as a holding means for the rear end of the pad if such a 10 holding means is desired.

Referring now specifically to Fig. 2: In this illustration, the continuous element 12 of Fig. 1 is divided into two parts 121 and 122 each cross-sectionally similar to the element 12 as previously described. The continuous element 12 of Fig. 1 keeps the pad from wrinkling transversely while the elements 121 and 122 permit such wrinkling when the material of the pad is very flimsy and wrinkles easily and no binder 20 is provided on the rear end of the pad. However, the working pressure on the pad is usually downward and there is little tendency for the pad to wrinkle between the elements 121 and 122.

20 The binder 23 (Fig. 4), shown as being continuous in Fig. 2, is made of material such as is described above for the element 12 and engages with the rear edge of the pad and supports the same across the rear end thereof and thereby prevents wrinkling of the pad and counteracts 30 whatever tendency there might be to wrinkling due to the lateral spacing of the elements 121 and 122.

The binder 23, also formed of one sheet of material, has the part 24 bent as shown with the 35 part 25 at one end thereof doubled up but not in contact with the part 24 and also has the part 26 similarly bent. The parts 25 and 26 also have teeth formed thereon similar to the teeth before described for the element 12 and 40 attaining the same function of engaging and gripping the edge of the pad.

The bracket 27, of material as previously described, has the part 28 to engage with the underside of the rear edge 29 of the table top, the part 45 30 to abut the rear end of the edge of the table, and the part 31 to rest on the table top and being bent upwardly to form the ear 32 which has a hole therethrough to receive one end of the spring 33 which has the other end 34 thereof 50 hooked into a hole in the binder 23. Any other elastic element, such as a rubber band, may be used in place of the spring. When the binder 23 is not made continuous, similar to the continuous element 12 being divided into the parts 55 121 and 122, it is best to use one bracket 27 and one spring 33 for each part of the binder to prevent the pad from being wrinkled especially when the element 12 is not continuous.

The pad 11 is to be laid onto a table top and 60 held thereon to form a base for mixing and rolling and kneading dough and other similar operations. The front edge 14 of the pad is inserted into the space 19 either before or after the element 12 is pushed over the edge of the table top, and is then folded over the outside of the part 18 and the pad is laid onto the table top. Due to the resiliency of the material of the element 12, the parts 17 and 21 engage the edge of the pad and hold the same therein. When 65 a pressure is brought onto the pad to move the same, the teeth engage the edge of the pad more firmly and hold the pad more firmly against movement thereof.

This pad moving pressure, away from the element 12 exerts a downward pressure on the part 18 and causes a more firm grip on the edge of the pad. The same effect is produced on the elements 121 and 122.

5 The element 23, when continuous, prevents wrinkling of the pad even when the spaced elements 121 and 122 are used and the spring 33 keeps a tension on the pad and thereby keeps the edge thereof in engagement in the element 12 and 121 and 122 as the case may be and keeps these elements against the edge of the table top. When the spring 33 is not used, the parts 15 and 28 may first be formed as indicated in dotted lines in Fig. 3 so that the same can be forcefully 15 pushed over the edge of the table top, instead of being loosely pushed thereover, and the resiliency of the material of the elements will cause the parts 15 and 28 to be held in place.

When the pad is to be removed from the holding 20 elements, a pad moving pressure, either longitudinally or sideways of the pad, will release the pad from the holding elements so that the same can easily be removed.

When the pad is to be stored, the elements may 25 be laid side by side and the pad wrapped around them to form one package. The whole package can also be covered or wrapped up in paper or cloth for storing.

30 The device shown and described embodies the present invention, is simple and inexpensive in structure, is easy of operation thereon and easy of assembling and disassembling and is sanitary.

Changes in structure and arrangement of elements from that herein shown and described can 35 be made within the scope of the present invention and the appended claims. Therefore, having shown and described the present invention and without limiting the present invention to the precise structure and arrangement of parts as shown 40 and described,

I claim:

1. A pad for a table top including an element to engage an edge of the table top when pushed thereover and having a part for engaging an edge 45 of said pad when the latter is inserted thereinto; said part having teeth thereon for engaging said edge of the pad more firmly when a pad moving pressure is brought upon said pad in one direction and releasing said pad from said element 50 when a pad moving pressure is brought upon said pad in another direction.

2. A pad for a table top, including an element to frictionally engage one edge of the table top and having jaws to grip one edge of said pad, 55 a binder gripping both sides of the opposite edge of said pad, a bracket engaging the opposite edge of said table top, and an elastic element between said binder and said bracket for keeping said pad flat relative to said table top.

3. An easily flexible pad for a table top, a locating and holding means for retaining said pad on the table top including, a flexible pad and an engaging element for one edge of the table top and one edge of said pad, a binder on the opposite edge of said pad, a bracket on the opposite edge of the table top, and a resilient element between said binder and said bracket; said pad and elements thereon being easily rolled up into a bundle and easily transported and easily stored and covered by said pad when so rolled up.
